SPARK PLUG SHIELD

Raymond L. Shumaker, Xenia, Ohio

Original application July 7, 1931, Serial No. 549,203. Divided and this application June 6, 1933, Serial No. 674,557

17 Claims. (Cl. 123—169)

(Granted under the act of March 3, 1883, as amended April 30, 1928; 370 O. G. 757)

The invention described herein may be manufactured and used by or for the Government for governmental purposes, without the payment to me of any royalty thereon.

5 The present invention relates generally to electrical apparatus and more particularly to apparatus adapted for use in connection with electric currents which are intermittent in character and/or in which the intensity of the current changes rapidly.

10 It is found that when the current changes rapidly in character or is intermittent, for example, in an ignition system for an internal combustion engine that, as a result of the electrical field set up by the high tension circuit and the spark discharge of the spark plugs and/or magneto, electrostatic or electromagnetic waves are propagated in the atmosphere surrounding the system to such an extent as to create considerable interference with proper reception in radio communication in apparatus that is in the vicinity of the ignition system. The high tension ignition systems essential in engines, particularly aircraft engines, produce 15 such violent electrical disturbances that radio reception and transmission have been found to be practically impossible. As a result therefore of these disturbances proper shielding of the ignition leads, the magneto and spark plugs of the system are imperative for the successful functioning of the radio equipment.

20 The use of shielding for the ignition cables, properly grounded, and for the magnetos of the ignition system are known to be old in the art and form no part of the present invention. To be effective the shield must, however, be continuous throughout the entire extent of the system including means for shielding the spark plugs in order that the disturbances produced by the spark discharge of the plugs may be confined so that they produce no interference with the radio equipment.

25 The main object therefore of the present invention is to provide means for enclosing the terminal portion of a spark plug to not only effect an electric bond between the shielding of a shielded cable and the ground portion of a spark plug, but also to completely insulate the terminal portion of the spark plug and cable, 30 confine the disturbances produced by the spark discharge of the plug and thereby form a continuous shield the purpose of which is to prevent the emanation of any electromagnetic waves into the atmosphere surrounding the plug as well as the remainder of the ignition system.

35 The invention is further characterized by providing shielding means adapted for ready attachment to or detachment from a spark plug which is so constructed and arranged that accumulation or deposits of any substance or material upon the insulated portion of the plug which may be a conductor of electric currents is substantially prevented.

40 A further object of the present invention is to provide shielding means of this character comprising a metallic sleeve which is held in good electric contact with the ground portion of the spark plug and being provided with an insulator on its inner surface, essentially a heat resisting sleeve of insulating material of high dielectric strength having intimate contact with the inner wall of the metallic sleeve to provide for maximum heat conductivity from the heated end of the plug.

45 A further object of the present invention is to so arrange the insulating material that the space between the inner wall of the metallic sleeve and the surface of the terminal portion of the plug is substantially completely filled. The use of an insulating sleeve constructed in the manner of the present invention provides for an insulator whose dielectric strength is not affected by moisture, oils or changes in atmospheric pressure, and if damaged in any way can be readily replaced independently of the spark plug.

50 The provision of insulating material in the inner wall of the metallic sleeve makes the same practically airtight by reason of the minimum of air space occurring between the inner wall of the shield and the spark plug; therefore accumulation of moisture upon the insulated surface of the plug is substantially prevented.

55 A further object of the present invention is to provide in a metallic sleeve of this character suitable coupling means comprising an insert of a material having high electrical conductivity for effecting a good electric contact between the conductor wire of the cable and the terminal end of the spark plug, particularly designed to effectively dissipate the heat from the terminal end of the spark plug to the external shielding in order to keep the temperature of the conductor wire adjacent the terminal of the spark plug at the minimum and prevent drying out and cracking of the insulation covering the wire. The insert is so constructed that diffusion of electrostatic stress over as great an area as possible may be effected, thus decreasing the charge density at any one point to a minimum.

charge per unit area is maintained as small as possible and any tendency to breakdown of the air gap and consequent flash over to ground is substantially prevented.

5 A still further object of the present invention is to provide a novel arrangement of parts so assembled as to retain the elements in their operative relation to one another yet permitting their disassociation for the purpose of cleaning 10 the spark plug, renewing worn or broken parts and the like.

With the above and other objects in view, which will appear as the description proceeds, the invention resides in the combination and 15 arrangement of parts and details of construction hereinafter described and claimed, it being understood that within the scope of what is claimed changes in the precise embodiment of the invention shown may be made without departing from the spirit of the invention.

In the drawing:

Fig. 1 illustrates a spark plug showing in longitudinal cross-section a shield embodying my invention;

25 Fig. 2 illustrates in a modified form a cross-sectional view of the shield per se;

Fig. 3 illustrates a further modified form of the shielding.

Referring more particularly to the drawing, 30 wherein corresponding parts are designated by like numerals throughout the several views thereof, 10 indicates a spark plug of any well-known make, which comprises generally the body portion 11 having a threaded portion at its lower end adapted for attachment to the cylinders (not shown) of an internal combustion engine, and a core 12 that comprises a stem or center electrode 13 and insulation material 13' surrounding said electrode. The outlet of said electrode is provided with a metal disk or terminal for making electrical connection with the ignition leads or cable of the ignition system of the engine.

40 The ignition cable 20 is provided with a metallic shield that is electrically grounded to the engine (not shown) by means of a spark plug shield or head that is electrically connected at one end to the metallic shield 20' and at its other end to the threaded portion 18 of the spark plug.

45 The spark plug shield or head comprises an outer metallic casing or covering, an inner shell of insulation material in intimate contact with the outer shield and a partition formed within the inner shell and suitably constructed to isolate the cable insulation from the spark plug terminal but through which electrical connection is made between the spark plug terminal and the cable terminal.

50 In the illustrations of the present invention the shield or head comprises a thin metallic sleeve 14 that completely surrounds the end portion of the cable and the terminal end of the spark plug etc, but which is electrically insulated from their terminal connections. This sleeve serves to electrically ground the cable shielding to the spark plug and for this purpose is formed at its lower end with a flange 16 to provide a shoulder against which a knurled lock nut 18 is adapted to bear, the latter being suitably provided with internal threads 17 adapted to engage with the threaded portion 18 of the spark plug. This arrangement permits the metallic sleeve to be held in good electric contact 75 with the grounded portion of the spark plug.

5 Provision is made for insulating the electrical connection between the cable 20 and the spark plug. This is accomplished by providing a suitable dielectric between the sleeve and the electrical connection between the cable and spark plug and is illustrated as an inner shell or lining 19 that is disposed within and extending substantially throughout the entire length of the inner wall of the sleeve 14. This lining is made of insulating material of non-carbonizing material having a high dielectric strength, preferably mica, the latter having intimate contact with the inner walls of the sleeve to provide for maximum heat conductivity to the said sleeve. The insulating material is of sufficient thickness 15 to practically fill the space between the metallic sleeve and the outer surface of the terminal portion of the spark plug to thereby maintain the same substantially in direct contact with the said surface.

20 This construction permits a shield which is practically airtight and by reason of the very small amount of air space which may occur between the terminal of the plug and shield, accumulation of moisture upon the insulating surface tending to foul the plug is substantially prevented. The material forming the outer sleeve is of sufficient thickness to permit a rigid construction and imparts sufficient strength to the structure to enable the sleeve to withstand considerable rough treatment without disturbing the proper functioning of the spark plug. It also acts as a protection for the insulated end of the spark plug. Its overall dimension as to width is such that it requires no additional space 25 in mounting the spark plug on the engine.

20 Provision is made for suitably protecting the cable insulation so as to prevent its deterioration by the heat within the shielded spark. Accordingly an inclosure for the end portion of 40 the cable insulation that is disposed within the shielded spark plug is provided to isolate the cable insulation from the spark plug center electrode. As illustrated in the several views of the drawing this inclosure is formed by providing a 45 partition within the shielded spark plug. Various means of inclosing the end portion of the cable insulation will be obvious to those skilled in the art without departing from the spirit of the invention. As illustrated in the several 50 views of the drawing, the partition is formed by providing an insert 22 that has intimate surface contact with the wall of the inner shell 19. This insert is preferably made of steel and is provided with a central opening to receive a closely fitting conductor part through which it is connected to the cable terminal. As shown in Fig. 1, the insert is connected to the cable by the terminal ends 23 of the cable conductor. As shown in Fig. 3, the terminal 24 of the cable and 55 a threaded element 24' constitutes the conductor part, the element 24' serving to connect the resilient contact member 26 and the cable terminal 23 to the insert.

60 The cable terminal is properly located and 65 detachably held in the spark plug shielding. This may be accomplished as illustrated in Fig. 1 by forming the upper portions of the metallic casing and inner shell to provide a shoulder 24" to support the insert. The upper portion 19' of the inner shell serves as a spacer. Between the upper end of the inner sleeve and the detachable connection 21 there is provided a ferrule or washer 19", which cooperates with the detachable connection 26 and the insert to 70 75

ground the cable shielding and to securely hold the inner shell in place. As shown in Fig. 2, the end of the conductor wire is secured to the inner end of the coiled spring 25, which makes 5 direct contact with the spark plug terminal 21, and by its spring action permits drawing down of the sleeve to make good electrical contact and a tight joint at its junction with the grounded portion of the spark plug.

10 The insert is so designed as to have as large an area as possible, the sides of which are in intimate contact with the inner surface of the insulating material. In this manner the cable insulation is baffled from direct contact with the 15 heat emanating from the center electrode and the heat is dissipated at a sufficiently rapid rate so that at the point of surface contact between the cable insulation and the insert the degree of heat will be such that it will have a negligible deteriorating effect upon the cable 20 insulation.

Additional separation between the cable insulation and the spark plug terminal to prevent heat deterioration of said cable insulation is obtained by providing a dead air chamber 25 between the cable insulation and the working walls of the sleeve. The dimensions of the dead air chamber are determined by the surface area of the insert and its thicknesses are sufficient to maintain the static charge density at any one point at a minimum by permitting the charge to spread out over the area of the insert. Flash over to ground under high voltage surge conditions is thus effectively prevented.

15 As shown in the drawing, the shielding of the cable is maintained in electrical contact with the metal sleeve enclosing the spark plug by means of a collar 26, which after the shielding of the cable is placed around the end of the cable is pressed into position as shown in Figs. 1, 2, 3 and 4. Figs. 5 and 6 show modified forms of connecting the shielding of the cable to the metal shield. It will be noted, the method of connecting the shielding of the cable to the shield enclosing the spark plug eliminates the use of soldering. As shown in Figs. 2 and 3 the sleeve 14 is maintained watertight by means of packing 27 which is interposed between the end of the sleeve 14 and the inner side 28 of the collar 26.

20 The present application is a divisional application of my pending application Serial No. 549,208, spark plug shield, filed July 7, 1931.

I claim:—

1. A shielded spark plug and electrical conductor cable for suppressing radio and other electrical disturbances comprising, a shielding for the plug and a shielding for the cable secured together near one end of said plug, the shielding for the plug being electrically connected to the grounded portion of the plug, the insulation for the conductor of said cable extending within the plug shielding, the terminal of said conductor being connected to the terminal of said plug, insulation material disposed within said plug shielding and around said cable, said insulation serving to electrically separate said shielding and cable-plug terminal connection and having surface contact with said shielding and baffling means contacting with said insulation material for inclosing the cable insulation to protect the same against impairment by the heat within said plug.

2. In a spark plug adapted to receive an insulated cable, a metallic body shell, an electrode 75 carrying core disposed therein, a head having

1 conductor part disposed therein and connected with said core electrode, said head having an external metallic shield for electrically connecting with said metallic body shell, and dielectric means for insulating said metallic shell from the terminal of said core electrode, said dielectric means including insulation material in intimate contact with said metallic body shell forming a closure with said conductor part for the cable insulation, said insulation material and conductor part serving to effectively conduct the heat from within said plug to said shell to prevent deterioration of the insulation of said cable and to prevent flash over between said shell and conductor part.

15 3. A shield for a spark plug adapted to electrically connect the shielding of a shielded cable to the ground of the spark plug comprising, a metallic casing, an insulation material disposed within said casing and having one aperture to receive an insulated portion of said cable, and a further aperture adapted to receive a conductor part that constitutes a closure for said aperture and serving to electrically connect the plug and cable terminals, said insulation material having intimate contact with the walls of said casing to thereby dissipate the heat and prevent deterioration of said cable insulation.

4. A shield for a spark plug adapted to electrically connect the shielding of a shielded cable to the ground of the spark plug comprising, a metallic casing, an insulation material disposed within said casing and having an aperture to receive an insulated portion of said cable, and a conductor part that constitutes a closure for said aperture serving to electrically connect the plug and cable terminals, said insulation material having a relatively thin cross-section over a sufficient contact area with the walls of said casing to thereby dissipate the heat and prevent deterioration of said cable insulation.

5. A shield for a spark plug adapted to electrically connect the shielding of a shielded cable to the ground of the spark plug comprising a metallic casing, an insulated material disposed within said casing and having an aperture adapted to receive insulation portion of said cable, and a further aperture to receive a conductor part, said conductor part serving to electrically connect the plug and cable terminals, said insulation material being so constructed and arranged as to provide with said spark plug a dead air chamber between said plug terminal and said cable insulation.

6. A shield for a spark plug adapted to electrically connect the shielding of a shielded cable to the ground of the spark plug comprising a metallic casing, insulation material disposed within said casing and having an aperture adapted to receive an insulated portion of said cable, and a further aperture to receive a conductor part, said conductor part serving to electrically connect the plug and cable terminals, said insulation material being so constructed and arranged as to provide with said spark plug a dead air chamber between said plug terminal and said cable insulation.

7. A shielded spark plug and electrical conductor cable for suppressing radio and other electrical disturbances comprising, a shielding for the plug and a shielding for the cable secured together near one end of said plug, the shielding for the plug forming a part of the grounded portion of the plug, the insulation for the conductor of said cable extending within the plug shielding, the terminal of said conductor
